UNITED STATES PATENT OFFICE.

NOLON I. CLARK, OF SEMINOLE, OKLAHOMA.

AIR HEATER FOR INTERNAL-COMBUSTION ENGINES.

Application filed April 27, 1928. Serial No. 273,356.

This invention relates to an attachment for an internal combustion engine, the general object of the invention being to provide means for controlling the air supply to the carburetor of the engine and also for heating the air and screening it before it passes to the carburetor so as to increase the efficiency of the engine.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a side view showing the device attached to a carburetor and to a portion of the exhaust manifold.

Figure 2 is a plan view of Figure 1.

Figure 3 is a section on line 3—3 of Figure 2.

Figure 4 is a section on line 4—4 of Figure 2.

Figure 5 is a section on line 5—5 of Figure 3.

In these views, the numeral 1 indicates an elongated casing which has an inlet opening 2 at one end thereof and the top and bottom portions of this end of the casing are provided with holes 3 through which a part of the exhaust pipe 4 passes. A substantially Y-shaped opening 5 is also formed in one side of the casing which communicates with the openings 3 for facilitating the placing of the casing on the pipe. The casing is clamped to the pipe by means of the U-bolt 6 and the brace 7.

A partition 8 of substantially L-shape is placed in the other portion of the casing so as to form an air chamber 9, one portion of the partition forming the top of the chamber, with this portion spaced from the top of the casing. This portion of the partition is formed with openings 10 through which air can pass from the casing into the chamber and the passage of air is controlled by the rotary shutter 11 pivoted to the top of the chamber and operated from a point adjacent the driver's seat through means which includes a wire 12 which has one end fastened to the shutter. Thus the shutter can be opened or closed or moved to a partly open

position so as to regulate the amount of air passing into the chamber.

A cap 13 fits in the extended lower end of the air chamber and has an internal flange 14 which receives a ring 15 placed on the base of the frusto-conical screen 16 which is located in the air chamber. The cap is formed with an elbow 17 which is adapted to be connected by the hose 18 to the air intake 19 of the carburetor A.

The casing is provided with a hinged cover part 20 which is arranged above the air chamber so that access to the parts may be had by opening this cover portion, suitable latch means 21 being provided for holding the cover part in closed position. The cap 13 is also detachably connected with the casing by the latch means 22.

From the foregoing it will be seen that air, entering the casing through the opening 2, will come in contact with that part of the exhaust pipe which passes through the casing so that the air will be heated. Then the air passes into the chamber and through the screen which removes all foreign matter from the air and then the air passes into the carburetor. Thus I have provided means for not only regulating the amount of air passing into the carburetor, but also means for heating the air and screening it before it enters the carburetor. This device can easily and quickly be put in place and through its use, the efficiency of the motor is greatly increased.

It is thought from the foregoing description that the advantages and novel features of my invention will be readily apparent.

It is to be understood that I may make changes in the construction and in the combination and arrangement of the several parts, provided that such changes fall within the scope of the appended claims.

What I claim is:—

1. An attachment for a motor vehicle comprising a casing having a part surrounding the exhaust pipe of the vehicle, said part having an opening therein for the admission of air so that the air is heated by coming in contact with the exhaust pipe, a chamber in the casing into which the air passes after being heated, means for regulating the amount of air passing into said chamber, a screen in said chamber for screening the air and means for conducting the air, after being screened, into the carburetor.

2. An attachment for a motor vehicle comprising a casing having a part surrounding

and attached to a part of the exhaust pipe of the motor, a chamber formed in another part of the casing and receiving air from the first part, said first part having an air inlet opening therein so that the air is heated before it enters said chamber, a rotary shutter for controlling the passage of air into the chamber, means for actuating the shutter from a point adjacent the driver's seat, a cap

fitting over the lower part of the chamber, 10 means for removably holding the cap in place, a screen in said chamber supported by the cap, an elbow carried by the cap and means for connecting the elbow to the air intake of the carbureter. 15

In testimony whereof I affix my signature.

NOLON I. CLARK.
